UNITED STATES PATENT OFFICE.

WINFIELD S. ODLE, OF LOS ANGELES, CALIFORNIA.

CASEMENT-WINDOW-OPERATING DEVICE.

1,103,218.

Specification of Letters Patent. Patented July 14, 1914.

Application filed September 23, 1912. Serial No. 721,803.

To all whom it may concern:

Be it known that I, WINFIELD S. ODLE, a citizen of the United States of America, residing at Los Angeles, in the county of Los Angeles and State of California, have invented new and useful Improvements in Casement-Window-Operating Devices, of which the following is a specification.

This invention relates to casement holders, and the object of the invention is to provide improved handle operating means which extend to a point within the window frame or opening, whereby the windows may be operated from within the room without interfering with the window screens, window shades or curtains and clamping means cooperating with the handle operating means whereby the latter is clamped in desired position as hereinafter described.

Referring to the drawings: Figure 1 is a front elevation of the inner side of a window showing my improved holder. Fig. 2 is a cross section on line x^2-x^2 , Fig. 1. Fig. 3 is an enlarged cross section on line x^3-x^3 . Fig. 2. Fig. 4 is a plan view in detail of the locking rod. Fig. 5 is a sectional view on an enlarged scale on line x^5-x^5 , Fig. 2, showing the parts in locked position. Fig. 6 is a view similar to Fig. 5, showing the parts in unlocked position. Fig. 7 is a vertical section on line x^7-x^7 , Fig. 1. Fig. 8 is a front elevation of the inner side of another form showing a single window provided with my improved holder. Fig. 9 is a section on line x^9-x^9 , Fig. 8, showing the single window wide open. Fig. 10 is a section on line $x^{10}-x^{10}$, Fig. 9.

1 designates the frame which is provided in the top with a channel rail 2 and at the bottom with a similar channel rail 2'. As clearly shown in Fig. 3, the rail 2 has a groove 3 with beveled walls 4. Slidably in each rail are two blocks 5, each block having beveled sides 6 which fit the beveled walls 4 of the associated rail, so that a perfect fit is secured and rattling is prevented. Each block 5 has flanges 7 which project over the upper edges of the rail 2'. One of the lower blocks 5 and the block above it, form a pair to which the adjacent casement 8 is pivoted at 9. The two casements 8 are connected by hinges 10.

Secured to each casement 8 is a fixed handle bracket 11 with a knob 12 by means of which the casement may be operated. Thus by pushing the brackets 11 toward each

other, the casements will be swung out into open position as indicated in Fig. 2, in which view the casements are shown as only partly open. They may be entirely opened by bringing the brackets 11 close together. To close the casements, the brackets 11 are moved the extreme distance apart.

Extending along the casing near the bottom of the casements is a grooved strip 13 and lying within the grooved strip 13 is a locking rod 14. The rod 14 has an intermediate half round portion 15, the two end portions 16 of the rod being round and being axially in line and having a revoluble bearing in the grooved strip 13. The brackets 11 project across the strip 13 immediately above the locking rod 14, and the locking rod 14 is provided with a handle 17 so that it may be turned to bring its bowed portion 15 upwardly against the under side of the brackets 11 and thereby exert a pressure against the brackets 11 which will frictionally hold them from movement in either direction and thereby lock the casements into any position into which they may be adjusted. A simple turn of the handle 17 will revolve the rod 14 and relieve its pressure against the brackets 11, permitting the casements to be adjusted. Fig. 5 shows the position of the locking rod when adjusted to bear against the bracket 11, while Fig. 6 shows the locking rod adjusted to release the brackets 11.

An important advantage of the device is that in addition to its simplicity and effectiveness and ease of operation, it is readily accessible and may be readily attached to the window after the casements are set, by any ordinary carpenter.

In the form shown in Figs. 8, 9 and 10, the casement is pivotally supported by means of a link 18 which is pivoted to a bracket 19 secured to the casement 20, the link 18 at its other end being pivoted at 21 to the frame 22. The casement 20 is pivoted at 9' to a sliding block 5', traveling in rail 2' in a manner similar to that previously described, and being operated similarly by a bracket 11' and knob 12'. Locking is performed by a locking rod 14' similar to that previously described. In this form the only difference is the exact positioning in the casement, secured by the link 18.

As the casement is opened, it pivots at 19 and slides the block 5' along the rail 2', the pivot 19 floating to accommodate this move-

ment. When the casement is fully opened, it stands in the position shown in Fig. 9. If desired, the casement may be locked by catch 23, as shown in Fig. 8, or it may be locked in any position desired by the locking rod 14.

In either form it will be noted that the handle members 11 or 11' extend under the stool to a point within the room so that the knobs of the handles are always accessible, no matter what the position of the window. This enables the window to be adjusted to any position, open or closed, without having to reach through the window opening. This obviates the necessity of operating the screen, window shade, or moving the curtains in any way whatsoever whenever it is necessary to adjust the window.

Each bracket 11 or 11' is rigidly secured to its casement and is so curved that its inner free end lies very close to the wall when the casement is closed, as clearly indicated in Fig. 7. This is a very valuable feature, because the bracket does not project into the room and offer any obstruction. Moreover, that end of the bracket which is secured to the casement is located so close to the pivot 9 of the casement, and the pivot 9 is slideable, that in the operation of the casement by the bracket, the line of travel of the free inner end of the bracket is almost parallel to the edge of the stool of the window, so that for any position of the window, the handle 12 of the bracket always lies close to the wall and does not project into the room. The free end of the bracket is also continued to a point beyond the vertical edge of the casement so that the bracket 11 does not project directly perpendicular from the casement, for if it did, it is apparent that when the casement was operated it would cause an

outward swinging movement of the free end of the bracket, which would cause it to strike the stool of the window and prevent proper operation. But being extended to a point beyond the edge of the casement, the opening movement of the casement causes the end of the bracket to move slightly inward into the room, away from the stool, thereby giving the proper degree of movement. When the casement is half opened, that is, at an angle of 45°, the handle 12 will stand its farthest distance from the stool, while further opening movement of the casement will cause the handle 12 to again move outward toward the stool, so that when the casement is in its extreme open position at 90° to the frame of the window, the handle 12 will again have been moved into its closest position to the stool.

What I claim is:

1. A casement window holder comprising a hinged sash having a fixed handle bracket whereby the sash is operated and clamping means for the handle bracket consisting of a pivoted cam rod adapted to bind on the handle bracket.

2. A casement window holder comprising a hinged sash having a fixed handle bracket whereby the sash is operated and clamping means for the handle bracket consisting of a pivoted cam rod adapted to bind on the handle bracket and a handle on the cam rod for operating it.

In testimony whereof, I have hereunto set my hand at Los Angeles, California, this 13th day of September, 1912.

WINFIELD S. ODLE.

In presence of—

G. T. HACKLEY,
VIOLET M. MURRAY.
